UNITED STATES PATENT OFFICE.

FORREST A. SUTHERLAND, OF MILLINOCKET, MAINE, ASSIGNOR TO GREAT NORTHERN PAPER COMPANY, OF MILLINOCKET, MAINE, A CORPORATION OF MAINE.

GUARD FOR PAPER-WINDING MACHINES.

Application filed December 5, 1927. Serial No. 237,645.

This invention relates to machines for winding paper in rolls wherein the roll of paper is supported on the peripheries of and is driven by a pair of driving rolls. The 5 invention has particular reference to guards or screens adapted to be located in front of the paper and winding rolls in position to prevent objects from being caught in the nip of the rolls.

10 One of the objects of this invention is the provision of a guard or screen which can be moved into a shielding position in front of the rolls and also into an elevated position in which the rolls are exposed, and re-

15 main in either position until moved therefrom, combined with an operating member, as a foot treadle, and mechanism by which the screen can be moved alternately between raised and lowered positions by successive 20 movements of the treadle in the same direction.

Another object of the invention is the provision of a guard for paper winders which is movable between roll-shielding and 25 exposing positions and is adapted to remain by gravity in whichever position it may be placed, and operating mechanism therefor including a treadle or equivalent member which is arranged to move the guard from 30 one toward the other position each time the treadle is depressed.

A further object of the invention is generally to improve the construction and operation of guards for paper winders and 35 operating mechanisms for said guards.

Fig. 1 is a front view of a paper winding machine embodying the invention.

Fig. 2 is a perspective view of the machine of Fig. 1, parts not essential to the understanding of the invention being omitted.

Fig. 3 is a detailed end view of the guard and its operating mechanism.

Fig. 4 is an enlarged detail of the construction of the guard and one of its supporting arms.

The winding machine with which the invention is associated includes a pair of end frames 10 having uprights 12. The frames are connected by an I-beam 14 disposed in 50 the front thereof and support between them a pair of horizontally-disposed parallel rollers 16 and 18 on which the paper roll 20 is adapted to be supported and rotated to wind up the paper, as is usual practice. The 55 guard embodying this invention comprises

a horizontal screen 22 which is substantially co-extensive with the width of the machine between said standards and has a vertical extent sufficient to prevent access to the rolls 16 and 18 and the paper roll 20 when it is 60 in normal position in front of said rolls. The screen is supported by a suitable frame which includes the bars 24 and 26 which are disposed at the ends of the screen and are extended upwardly between the uprights 12 65 and have rearwardly directed upper ends which overlie and are terminated somewhat in the rear of a horizontal screen-supporting shaft 28 journaled in said uprights. Arms 30, Figs. 3 and 4, are fixed to the rear ends 70 of said bars 24 and 26 and have their lower ends reflexed to partially encircle said shaft and are clamped thereto by yokes 32 and bolts 34 which pass through said yokes and arms. 75

In the normal working position of the guard, the lower edge thereof rests upon the beam 14 and the arms 30 are inclined upwardly and rearwardly from said shaft 28 as indicated most clearly in Figs. 3 and 4. 80 The weight of the guard is to some extent but not entirely counterbalanced by weights 36 which are adjustably screw threaded on brackets 38 fixed to said arms 30 by the aforesaid bolts 34 and are extended rearwardly of said shaft somewhat below said arms and are also inclined upwardly and rearwardly. The guard is adapted to be raised by the rotation of said shaft 28 from the position shown in Figs. 2 and 3 into a 85 position wherein the center of mass of the guard is entirely to the right of the shaft 28 in which position it will be maintained by the engagement of the free ends of the arms 30 with a stop member as an angle beam 40 90 which is carried by the uprights 12 of the frame below and in proximity to the shaft 28 as indicated in dotted lines Fig. 3.

The guard is adapted to be alternately raised and lowered by successive depressions 100 of a foot treadle 42 which is pivoted at 44 to one of the end frames 10 of the machine and has its treadle portion located at the front of the frame beneath the beam 14. A rod 46 is pivotally connected at its lower end 48 with an intermediate part of said treadle and extends vertically upward beneath one of said arms 30 and has divergent front and rear ends 50 and 52 respectively. Flexible cables 54 and 56 are connected re- 110

spectively with said divergent ends and extend upwardly and have connections 58 and 60 respectively which are screw threaded on the bolts 34 and thus are located on opposite sides of the shaft 28 so that a pull on one cable tends to rotate the shaft in one direction and a pull on the other cable tends to rotate the shaft in the opposite direction. Turn buckles 62 and 64 are interposed in 10 said cables intermediate their ends to adjust the respective lengths thereof.

The operation of the device is essentially as follows: When the guard is in operative position as illustrated in Fig. 2 and the 15 treadle is up, the rear cable 56 is taut while the front cable 54 is slack. When the treadle 42 is depressed it pulls down the arm 30 and rotates the shaft 28 in a clockwise direction, Figs. 2 and 3, thereby raising the 20 guard; and the extent of movement of the treadle is adapted to be sufficient to move the guard upwardly and rearwardly until the center of gravity of the guard passes to the right of the vertical line through the 25 shaft 28. The guard then moves further in the same direction by gravity, independent of the cable 56, thus transferring the weight of the guard from the rear cable 56 to the front cable 54. When the treadle is re- 30 leased, the guard moves further in the same direction and comes up against and is held by the stop beam 40 and the front cable 54 is now taut and the rear cable 56 is now slack. When the guard is to be lowered the 35 treadle 42 is again depressed. This places the front cable 54 in tension and causes the shaft 28 to be rotated in a counterclockwise direction, thus moving the guard forwardly until the center of gravity is in front of the 40 shaft 28 whereupon the weight of the guard is transferred from the front to the rear cable. Raising the treadle then serves to let the guard drop by its weight onto the I-beam 14.

45 The turn buckles 62 and 64 serve to adjust the length of the respective cables so that the weight of the guard can pass from one cable to the other without any great amount of free movement.

50 I claim:

1. A paper winding machine having winding rolls, in combination with a guard normally disposed in front of said rolls and adapted to be elevated away from such position, an operating member for raising and lowering said guard, and operating mechanism connecting said operating member and guard effective to move said guard alternately between raised and lowered positions 55 upon successive movements of said operating member in the same direction.

2. A paper winding machine having winding rolls, a guard normally disposed in lowered position in front of said rolls and adapted 60 to be elevated above said rolls and to be

maintained by gravity in any one of said positions, a treadle for both raising and lowering said guard, and operating mechanism connecting said treadle and guard operative to move said guard out of either of its two 70 positions on successive depressions of said treadle.

3. A paper winding machine having winding rolls, a pivotally supported guard movable between a normal low position in front 75 of said rolls and an elevated position, an operating treadle for said guard, and lost motion connections between said treadle and said guard disposed on opposite sides of its pivotal axis. 80

4. A paper winding machine having winding rolls, a pivotally supported guard movable between a normal low position in front of said rolls and an elevated position, an operating treadle for said guard, and an operative 85 connection between said treadle and said guard including a pair of flexible cables connected with said treadle and with said guard on opposite sides of its pivotal axis.

5. A paper winding machine having winding rolls, a pivotally supported guard movable between a normal low position in front of said rolls and an elevated position, an operating treadle for said guard, an operative 90 connection between said treadle and said guard including a pair of flexible cables connected with said treadle and with said guard on opposite sides of its pivotal axis, and means to adjust the lengths of each flexible cable independently of the other. 95

6. A winding machine having winding rolls, a pivotally supported guard movable from a normal low position in front of said rolls to an elevated position and adapted to remain by gravity in any one of said positions, a treadle adapted to be depressed to raise and also to lower said guard, and operating mechanism connecting said treadle and said guard arranged to shift the effective 105 connection between said treadle and guard from one to the other side of the pivotal axis of said guard in accordance with the position thereof. 110

7. A winding machine having winding rolls, a pivotally supported guard movable from a normal low position in front of said rolls to an elevated position and adapted to remain by gravity in any one of said positions, a treadle adapted to be depressed to raise and also to lower said guard, and operating mechanism connecting said treadle with said guard arranged to shift the effective connection between said treadle and guard from one to the other side of the pivotal axis of said guard in accordance 120 with the position thereof, said mechanism including a pair of flexible cables connected with said treadle and with said guard on opposite sides of its pivotal axis, said cables adapted alternately to transmit movement 125 130

between said treadle and guard in raising and lowering it.

8. A winding machine having winding rolls, a guard movable from a normal low position in front of said rolls to an elevated position and adapted to be maintained by gravity in any one of said positions, said guard having a pair of supporting bars extended upwardly and rearwardly thereabove, 10 a horizontally disposed rotatable shaft located beneath the rear ends of said bars, and having rearwardly and upwardly extended arms fixed to said bars, a treadle for raising and also for lowering said guard, 15 and a pair of flexible cables connected with said treadle and with one of said arms on opposite sides of said shaft.

9. A winding machine having winding rolls, a guard movable from a normal low 20 position in front of said rolls to an elevated position and adapted to be maintained by gravity in any one of said positions, said guard having a pair of supporting bars extended upwardly and rearwardly thereabove, 25 a horizontally disposed rotatable shaft located beneath the rear ends of said bars and fixed thereto, a treadle for raising and also for lowering said guard; and a pair of flexible cables connected with said treadle 30 and with said shaft on opposite sides thereof.

10. A winding machine having winding rolls, a guard movable from a normal low position in front of said rolls to an elevated 35 position and adapted to be retained by gravity in any one of said positions, a rotatable shaft supporting said guard, an arm fixed to said shaft and extended in opposite directions therebeyond and inclined upwardly and rearwardly when the guard is in its normal low position, a normally elevated treadle for raising and also for lowering 40 said guard, and a pair of flexible cables

connected with said treadle and with said inclined arm on opposite sides of said shaft. 45

11. A winding machine having winding rolls, a guard movable from a normal low position in front of said rolls to an elevated position and adapted to be retained by gravity in any one of said positions, a rotatable 50 shaft supporting said guard, an arm fixed to said shaft and extended in opposite directions therebeyond and inclined upwardly and rearwardly when the guard is in its normal low position, a treadle for raising 55 and also for lowering said guard, and a pair of flexible cables connected with said treadle and with said inclined arm on opposite sides of said shaft, said cables having means interposed between the ends thereof to vary 60 the effective lengths thereof.

12. A winding machine having winding rolls, a guard movable from a normal low position in front of said rolls to an elevated position and adapted to be retained by gravity in any one of said positions, a rotatable 65 shaft supporting said guard, an arm fixed to said shaft and extended in opposite directions therebeyond and inclined upwardly and forwardly when the guard is in its normal low position, a treadle for raising and also for lowering said guard, a rod having a connection at its lower end with said treadle and having divergent front and rear upper 70 ends located beneath said rotatable shaft and said arm, and a pair of flexible cables connected with said front and rear upper ends of said rod and also respectively with the front and rear ends of said arm on opposite sides of said shaft, said flexible cables 80 having means interposed between the ends thereof to adjust the effective lengths thereof.

In testimony whereof, I have signed my name to this specification.

FORREST A. SUTHERLAND.
